(57) **CLAIM**

The ornamental design for an irrigation valve, as shown and described.

DESCRIPTION

FIG. 1 is a perspective view of a first embodiment of an irrigation valve with flow control showing our new design;

FIG. 2 is a front elevational view of the invention illustrated in FIG. 1;

FIG. 3 is a left elevational view of the invention illustrated in FIG. 1;

FIG. 4 is a right elevational view of the invention illustrated in FIG. 1;

FIG. 5 is a back elevational view of the invention illustrated in FIG. 1;

FIG. 6 is a top plan view of the invention illustrated in FIG. 1;

FIG. 7 is a bottom plan view of the invention illustrated in FIG. 1.

FIG. 8 is a perspective view of a second embodiment of an irrigation valve without flow control showing our new design;

FIG. 9 is a front elevational view of the invention illustrated in FIG. 8;

FIG. 10 is a left elevational view of the invention illustrated in FIG. 8;

FIG. 11 is a right elevational view of the invention illustrated in FIG. 8;

FIG. 12 is a back elevational view of the invention illustrated in FIG. 8;

FIG. 13 is a top plan view of the invention illustrated in FIG. 8; and,

FIG. 14 is a bottom plan view of the invention illustrated in FIG. 8.
